UNITED STATES PATENT OFFICE.

WARREN E. COOMBES, OF BOSTON, MASSACHUSETTS, AND EDWARD H. LERCHEN, OF EAST ORANGE, NEW JERSEY, ASSIGNORS TO UNITED SHOE MACHINERY CORPORATION, OF PATERSON, NEW JERSEY, A CORPORATION OF NEW JERSEY.

SHOE RACK.

Application filed March 16, 1925. Serial No. 15,963.

This invention relates to shoe racks of the type employed for storing and transporting shoes between successive operations of manufacture.

5 To facilitate the preliminary attachment of wood heels to lasted shoes by means of adhesive material, use is made, frequently, of what is known as a C-clamp for the purpose of temporarily clamping the heel in 10 proper relation to the lasted shoe, until the adhesive is dried. At the present time, in the use of such clamps, it is common practice to place the lasted shoe with its heel clamp upon a shelf rack during the drying 15 operation. Due to haphazard or careless placing of the shoes on the rack as well as to jostling if the racks are moved, considerable damage is often done by the striking 20 of the clamps against uppers of adjacent shoes.

It is therefore an important object of our invention to provide a rack for the reception of shoes with attached heel clamps, so constructed as to eliminate the trouble above 25 described.

To this end, the present invention provides a novel rack in which, in addition to members such as pins arranged to support shoes upright in the rack, means are provided for 30 positioning and holding heel clamps attached to the shoes in order to prevent any undesirable displacement of the shoes and clamps. In the illustrated construction, a pin bar carrying the shoe-supporting pins is 35 provided with slots between each pair of pins adapted to receive the shoe clamps and operating to prevent both lateral and rotational movement of the clamps and shoes. At the same time, the pin bar is tilted up- 40 wardly so that the shoes and clamps supported by the pins will tend to slide toward the bar, thus preventing liability of the shoes sliding or being jostled out of engagement with the pins.

45 In the accompanying drawings,—

Fig. 1 represents a portion of a shoe rack according to our invention with a lasted shoe and clamp shown in position thereon, and

50 Fig. 2 represents a portion of a frame supporting a tilted pin bar according to our invention.

A pin bar 10 forming part of a frame, not shown, supports a plurality of pins 12

arranged in pairs. Midway between the 55 pins of each pair the bar is provided with vertical slots 14 adapted for the reception of the backs of clamps such as clamp 16 attached to a lasted shoe 18. The pins of each pair converge at their outer ends to 60 conform to the general shape of the last and are arranged to provide an even seat for supporting shoes placed thereon bottoms up with heels extending toward the pin bar.

The bar 10 may be supported in any convenient manner, such as by a frame of the type disclosed in United States Letters Patent No. 1,447,228, granted May 6, 1923, on application of C. B. Tibbetts. The illustrated bar is supported in such manner as 65 to be slightly tilted with respect to the horizontal frame member 20, so that a lasted shoe and clamp placed on the pins will tend 70 to slide toward the bar, and the clamp will be moved into engagement in a slot. 75

In the use of the rack a shoe is placed on a pair of pins bottom up in such manner that the forepart of the shoe is supported upon the outer ends of the pins, and the heel part extends inwardly into a position adjacent to the pin bar. The heel clamp, projecting rearwardly, is engaged in one of the slots 14 in the pin bar 10, holding the shoe 80 against lateral or rotational movement, thus preventing possibility of contact between adjacent shoes and clamps. 85

Having described our invention, what we claim as new and desire to secure by Letters Patent of the United States is:—

1. A shoe rack comprising a pin bar, 90 pins extending laterally therefrom constructed and arranged to support shoes having heel clamps attached thereto, and slots in the bar between the pins arranged for the reception of the clamps for preventing lateral or rotational movement of the shoes in the 95 rack.

2. A shoe rack comprising a pin bar, a plurality of pins arranged in pairs supported thereon, and a slot in the pin bar for 100 each pair of pins, the pins and slots being so constructed and arranged that when a shoe is placed in position on the pins the heel clamp attached thereto is engaged in one of the slots in the bar. 105

3. In a device of the class described, a bar, means on the bar constructed and arranged for supporting a lasted shoe, the

bar having means for receiving a heel clamp attached to the shoe and engaging the heel clamp to maintain the shoe and clamp in an upright position in the rack.

5. 4. In a device of the class described, a bar, a plurality of members carried by the bar for supporting shoes, and slots in the bar to receive and position clamps attached to shoes for holding the shoes against lateral or rotational movement in the rack, the bar being tilted above the horizontal for ensuring engagement of the clamps with the slots.

5. In a shoe rack, the combination with a pin bar, of a plurality of pairs of pins projecting laterally from the bar, each pair of

pins constructed and arranged to support between them a shoe having a clamp attached thereto with the shoe in its inverted position, its heel end extending toward the pin bar, and a plurality of clamp-receiving slots in the pin bar located, respectively, between the pins of each pair of pins.

In testimony whereof I, the said WARREN E. COOMBES, have signed my name to this specification.

WARREN E. COOMBES.

In testimony whereof I, the said EDWARD H. LERCHIEN, have signed my name to this specification.

EDWARD H. LERCHIEN.
